(57) **CLAIM**

The ornamental design for a filter, as shown and described.

DESCRIPTION

FIG.1 is a perspective view of a filter showing our new design;
 FIG. 2 is a bottom perspective view of the filter of FIG. 1;
 FIG. 3 is a front view of the filter of FIG. 1;

FIG. 4 is a rear view of the filter of FIG. 1;
 FIG. 5 is a left side view of the filter of FIG. 1;
 FIG. 6 is a right side view of the filter of FIG. 1;
 FIG. 7 is a top view of the filter of FIG. 1; and,
 FIG. 8 is a bottom view of the filter of FIG. 1.
 The broken lines in the drawings depict environmental subject matter that forms no part of the claimed design.
